UNITED STATES PATENT OFFICE.

CLARENCE H. McCAGHEY, OF ROCK RAPIDS, IOWA.

EYE-SHIELD ATTACHMENT FOR CAPS.

1,219,972.

Specification of Letters Patent. Patented Mar. 20, 1917.

Application filed September 30, 1916. Serial No. 23,110.

To all whom it may concern:

Be it known that I, CLARENCE H. McCAGHEY, a citizen of the United States, residing at Rock Rapids, in the county of Lyon and State of Iowa, have invented new and useful Improvements in Eye-Shield Attachments for Caps, of which the following is a specification.

This invention relates to a combined eye shield and goggle for automobilists to protect the eyes of an operator from the intense rays of light which are propagated from the lamps of an approaching automobile, and furthermore to shield the eyes from the wind and dust.

The chief characteristic of this invention is to provide a device of the above character which is adapted to be attached to a head covering such as a cap or the like, whereby the shield may be supported in convenient position for the application of the shield to the eyes.

Another characteristic of this invention is to provide a device of this character in which the attaching means for the shield is of novel construction to lock the shield in folded or open position against accidental displacement.

The invention further consists in providing the shield having a guard in which a portion thereof is colored to absorb the intense rays of light from luminous objects.

Other objects of the invention will appear as the specification is read in connection with the accompanying drawings, in which:

Figure 1 is an edge elevation of the shield showing the same applied to a cap.

Fig. 2 is a front elevation of the shield detached from the cap.

Fig. 3 is a detailed view of the connection between the shield and the attaching means.

Fig. 4 is a detailed view of the shield showing the same in folded position.

Referring to the drawings in detail, A designates a head covering which is in this instance in the form of a cap, the cap being provided with the usual curved peak 1. Secured to the underside of the peak and extending longitudinally of the same is an attaching bar 2, the bar being curved longitudinally throughout its length to conform to the contour of the peak and provided with openings 3 at the opposite ends thereof which are adapted to receive the fastening members 4, the fastening members extending through the peak 1

whereby the bar 1 will be held securely upon the cap as will be understood. In this instance the fastening members 4 are in the form of screws upon which are threadedly mounted the nuts 4', the latter being engageable with the bar whereby the bar may be detachably held upon the cap as will be understood. The opposite ends of the bar 2 are provided with the angularly disposed apertured ears 5, the ears depending from the underside of the peak and having their confronting faces formed with transversely extending grooves 6, the grooves being arranged at the medial portion of the ears and in horizontal alignment with the apertures. The grooves may be formed either by bending the ears outwardly and inwardly or by grooving the ears upon their confronting faces, I having shown the former structure in this instance.

Swingingly mounted upon the bar 2 is my improved form of shield which comprises in this instance a frame 7 which is formed of a single length of resilient wire bent between its ends to provide the substantially semicircular portions 8 and the reversely disposed curved portion 9, the latter connecting the curved portions 8 as clearly shown in the drawings. The opposite ends of the frame 7 terminate in laterally disposed pintles 10 which are loosely mounted within the ears 5 whereby the frame will be swingingly supported upon the bar to permit the moving of the frame to active or inactive position. In this instance the frame 7 is curved longitudinally in the form of an arc so that when the frame is in folded position against the underside of the peak 1, the frame will lie contiguous thereto, to prevent the shield from interfering with the vision of the wearer when the shield is in inactive position. Mounted upon the frame 7 and secured thereto in any suitable manner is the shield lens 11, which is in this instance formed of transparent celluloid, the upper portion of which is colored as at 12 whereby the eyes will be shielded from the rays of light of great intensity. The lens 11 is in this instance formed from a single sheet of celluloid or other suitable material and is secured to the frame 7 by means of stitching 13, although I wish it to be clearly understood that any suitable means may be employed for securing the lens upon the frame.

In operation, the cap is arranged upon the head in the usual manner, the shield when

in active position is depending from the underside of the peak as clearly shown in Fig. 1 of the drawings, and, when in inactive position, the shield will assume a horizontal position and lie contiguous to the underside of the peak. It will be evident from the construction of the frame for the shield and the particular construction of the confronting faces of the ears⁵, that when the shield is in an inactive position the frame, owing to its inherent resiliency, will continually force its ends outwardly and into engagement with the confronting faces of the ears so that when the shield is in inactive position the opposite ends of the frame will be disposed within the grooves 6 thus locking the shield against accidental displacement. As the frame 7 exerts the constant pressure upon the confronting faces of the ears it will be evident that when the shield is in active position, the frictional engagement between the frame and the ears will cause the shield to be held in a vertical position against accidental displacement. It is to be understood that the shield may be readily removed by compressing the opposite ends of the frame

whereby the pintles 10 may be readily removed from the openings within the ears.

It is thought from the foregoing taken in connection with the accompanying drawings ³⁰ that the construction and operation of my device will be apparent to those skilled in the art, that minor changes in size, shape, proportion and minor details of construction may be made without departing from ³⁵ the spirit and scope of the appended claim.

What I claim is:—

In combination with a head covering, an attaching device comprising a rigid bar secured to the head covering and having the ⁴⁰ opposite ends thereof terminating in angularly disposed apertured pivot ears, the confronting faces of said ears being formed with grooves, an expansible frame, pintles formed on the frame and mounted in the apertures ⁴⁵ of said ears, said frame being engageable with the grooves to lock the same in folded position, and an eye shield carried by the frame.

In testimony whereof I affix my signature. ⁵⁰

CLARENCE H. McCaughey.
